(57) **CLAIM**

The ornamental design for a bathtub stopper, as shown and described.

DESCRIPTION

FIG. 1 is a front, left, top perspective view of a bathtub stopper, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, left, top perspective view thereof in an alternate configuration.

The dashed broken lines in the figures are for the purposes of illustrating portions of the bathtub stopper and form no part of the claimed design.
